DANGER SIGNAL

Original Filed April 26, 1920

INVENTOR

P. G. Myers

By: *Fraser, Merkel, Laywell & Bond* ATTORNEYS

UNITED STATES PATENT OFFICE.

PARKE G. MYERS, OF CAIRO, OHIO, ASSIGNOR TO THE AUTOMATIC SIGNAL & SIGN COMPANY, OF CANTON, OHIO, A CORPORATION OF OHIO.

DANGER SIGNAL.

Original application filed April 26, 1920, Serial No. 376,673. Divided and this application filed June 27, 1921. Serial No. 480,902.

The present invention relates to signaling devices, such as are adapted to be located at dangerous points along the roadway or at intersections or cross roads or railroad crossings, and is a division of my pending application serial No. 376,673, filed April 26, 1920, and relates more especially to the reflector which forms a part of the signaling device.

The objects of the present invention are to provide a signaling device of the general character referred to which will reflect the rays of light from the headlight of an approaching vehicle, back to the operator of the vehicle or to the operator of another vehicle approaching from another direction.

Another object of the invention is to provide such a signaling device with a transparent color reflecting medium including a plurality of angular or convex and concave surfaces provided with a mirror back and arranged to reflect rays of light in different directions.

The above together with other objects which will be apparent from the following description and the accompanying drawings, may be attained by forming the reflector of a single sheet of colored transparent material pressed into the form of a plurality of hollow shallow pyramids, each comprising four triangular reflecting surfaces arranged to receive the light, and reflect it in a different direction, the reflected rays being passed through the colored reflecting medium, a suitable mirror back being applied to the rear or inner face of the colored medium.

With these objects in view, the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is a front elevation of a signaling device provided with a reflector embodying the invention; and

Fig. 2, a sectional view through the reflector upon an enlarged scale.

A practical embodiment of the invention is disclosed in the accompanying drawings, forming a part of this specification in which similar numerals of reference indicate corresponding parts throughout the several views.

The signaling device is preferably mounted upon a post 1 which may be imbedded in the ground at any desired point along a roadway or at a cross road or at a railroad crossing. The frame 2 which contains the reflector may be provided with a collar 3 which receives the upper end of the post 1 and is held in any desired radial position thereon by means of the set screw 4. The reflecting medium indicated generally by the numeral 5 comprises a single sheet of colored glass or other transparent material which is coated upon its rear surface with mercury or the like in the manner of a mirror as shown at 6.

This reflecting medium is pressed into the form shown in the drawings producing a plurality of rectangular sections indicated generally by the numeral 7, each section being in the form of a shallow pyramid comprising a plurality of triangular faces 8 set at angles to each other, the vertex of each pyramid being preferably convex, as shown at 9.

By forming the face of the reflecting medium in the manner shown, all of the rays from an approaching light will strike upon the reflector and be reflected back to the operator of an approaching vehicle, being colored by passing through the colored reflecting medium. When a light is thrown upon the signal, it will appear as a brilliant colored square, instantly attracting the attention of persons approaching the signal and giving warning of danger.

I claim:—

1. In a signaling device, a support, a frame mounted upon the support, and a reflecting plate carried in the frame comprising a transparent, colored, medium pressed into a series of hollow pyramids having a reflecting medium upon the hollow sides thereof forming a plurality of angularly disposed reflecting surfaces arranged to diverge rays of white light falling thereon and color the light which is reflected back therefrom.

2. In a signaling device, a support, a frame mounted upon the support, and a reflecting

- plate carried in the frame comprising a transparent, colored medium including a plurality of hollow pyramidal units having reflecting mediums upon their hollow sides, 5 each unit having a plurality of angularly disposed reflecting surfaces arranged to diverge rays of white light falling thereon and color the light which is reflected back therefrom.
- 10 3. In a signaling device, a reflecting plate comprising a colored transparent medium pressed into a series of hollow pyramids having a reflecting medium upon the hollow sides thereof forming a plurality of angularly disposed reflecting surfaces arranged to diverge rays of white light falling thereon and color the light which is reflected back therefrom.
- 15 4. In a signaling device, a reflecting plate comprising a colored transparent medium including a plurality of hollow pyramidal units, a reflecting medium upon the hollow side thereof, each unit having a plurality of angularly disposed reflecting surfaces arranged to diverge rays of white light falling thereon and color the light which is reflected back therefrom.
- 20 5. In a signaling device, a reflecting plate comprising a colored transparent medium including a plurality of hollow pyramidal units, a reflecting medium upon the hollow side thereof, each unit having a plurality of angularly disposed reflecting surfaces arranged to diverge rays of white light falling thereon and color the light which is reflected back therefrom.
- 25 6. In a signaling device, a reflecting medium comprising a transparent colored plate pressed into a hollow pyramidal form and a reflector of corresponding shape upon the rear side of said transparent plate.
- 30 7. In a signaling device, a reflecting medium comprising a transparent colored plate of hollow pyramidal form having a mirror back upon its concave surface.
- 35 8. In a signaling device, a reflecting medium comprising a transparent colored plate comprising a plurality of shallow, hollow pyramids and a mirror back upon the concave surfaces thereof.
- 40 9. In a signal device, a reflecting medium comprising a transparent, colored plate pressed into a hollow, pyramidal form having a rounded apex and a reflector of corresponding shape upon the rear side of said transparent plate.
- 45
- 50
- 55
- In testimony that I claim the above, I have hereunto subscribed my name.

PARKE G. MYERS.
